UNITED STATES PATENT OFFICE.

ARTHUR ROBERT THOMAS WOODS, OF HARROW, NEAR LONDON, ENGLAND.

SHIP'S BOAT OR THE LIKE.

1,232,155.

Specification of Letters Patent.

Patented July 3, 1917.

Application filed August 29, 1913. Serial No. 787,837.

To all whom it may concern:

Be it known that I, ARTHUR ROBERT THOMAS Woods, a subject of the King of Great Britain, and residing in Harrow, near 5 London, England, have invented certain new and useful Improvements in or Relating to Ships' Boats or the like, of which the following is a specification.

This invention has reference to ships' 10 boats or the like and relates more particularly to the arrangement of the water-tight buoyancy chambers or tanks with which such boats are generally fitted, and to bulkheads arranged in the boat in conjunction with 15 the buoyancy tanks.

According to the ordinary construction, 20 the buoyancy tanks, which are water-tight and intended to insure buoyancy even if the boat be filled with water, are located along each side of the boat. In this position they are very much exposed to risk of being damaged by impact of the boat against the ship's side while being launched, or by collision when afloat, or even by being struck 25 by a heavy sea; such damage would generally destroy the water-tightness and buoyancy of the tank, and not only render it useless for the purpose intended, but would make it a positive source of danger by loading 30 the boat on one side and so endangering its stability.

According to my invention, instead of locating the buoyancy tanks in the usual way along the sides of the boat, I locate them 35 along the center line thereof where they are in the position best shielded from the risks mentioned.

In the case of a boat with a steel shell, I 40 preferably make the tanks integral with the boat, in the form of an inverted U trough with its lower edges flanged outwardly and riveted to the bottom of the boat shell on each side of the center line, and I find it advisable to fit an independent water tight 45 bottom to the tank a little above the bottom of the boat.

The tank is thus made double-bottomed and the risk of its being pierced by impact of the bottom of the boat against a rock or 50 submerged wreckage is minimized.

The space inclosed as described is divided 55 water-tight by transverse plates so as to form a number of independent compartments or buoyancy tanks. The tank is preferably carried as high as the thwarts will permit, or in some cases even higher, and

each compartment is provided with a man-hole with a lid adapted to be jointed water-tight and giving access for cleaning, painting, or repair.

The tanks preferably stop off short of each end of the boat and should have sufficient buoyancy to keep the boat afloat when fully loaded although filled with water.

As an additional safeguard against the 65 destruction of the boat's buoyancy by collision or other accidents, I prefer to fit a number of water-tight partitions or bulkheads extending from the central buoyancy tank to the shell of the boat and carried as 70 high as practicable, so as to subdivide the boat into a number of compartments, and I specially arrange these bulkheads as herein-after described, so as to minimize risk of 75 injury to the buoyancy tanks by thrust conveyed through the bulkheads resulting from collision or other accidents.

I have illustrated my invention as applied 80 to a seamless steel life boat in the accompanying drawings, in which Figure 1 is a plan, the lower half being in section on the line A, A, of Fig. 3, and Fig. 2 is an elevation in section on the line B, B, of Fig. 1; Fig. 3 is a transverse section on the line C, C, of Fig. 1.

1 is the shell of the boat and 2 are seats forming a partial deck carried on brackets 3 arranged around the gunwale, and extended at 2^a so as to deck in the ends of the boat; 4 are the usual thwarts which are fixed 90 across the boat to the seat or deck 2.

5 is the buoyancy tank, extending symmetrically along the center line of the boat for the greater part of the length thereof. It is of inverted U form, closed at the ends 95 by the end plates 5^a and closed at the bottom by the bottom plate 5^b, all riveted water-tight together. The sides and the end plates 5^a are carried down to the bottom of the boat where they are flanged outwardly 100 and riveted water-tight to the boat shell, thus making the tank double-bottomed as already described.

The tank is stiffened by gusset plates 6 and is divided by the transverse water-tight 105 division plates 7 so as to form a number of independent water-tight compartments or buoyancy tanks. The various compartments are provided with manholes and lids 8 adapted to be jointed water-tightly in any 110 of the well known ways.

9 are the water-tight partitions or bulk-

heads, previously referred to, extending from the buoyancy tanks to the shell of the boat, to both of which they are riveted, and carried as high as practicable so as to divide 5 the boat into a number of compartments.

Two of these bulkheads extend along the center line from the ends of the buoyancy tank to the bow and stern respectively, so as to divide the boat into two compartments 10 longitudinally. Another pair extend transversely about amid-ships from the buoyancy tank to the shell of the boat, thus dividing it into four compartments, any one of which might become water-logged without impairing 15 the buoyancy of the others.

It will be understood that the buoyancy of the central tank should be preserved at all costs, as this buoyancy is ultimately relied upon to keep the boat from foundering. 20 Hence the buoyancy tank is located centrally and stops off at some distance short of the ends of the boat, so that if the main structure of the boat should be staved in or otherwise damaged, the tank would remain unimpaired. 25

As the connection of the central tank to the ends and sides of the boat might render the tank liable to injury by thrust conveyed through the bulkheads, I specially arrange 30 the latter so as to avoid this danger. I accordingly make them of a ductile material, as thin as their purposes will permit, and preferably curve or corrugate them and arrange them obliquely to the tank, with 35 easy bends at their ends, as shown in the case of the transverse bulkheads in Fig. 1. So arranged, the bulkheads will bend or buckle or crumple under thrust without injuring the tank.

40 Four bulkheads are shown in the drawings, which are usually sufficient for a boat of moderate size, but of course the number may be increased or diminished to suit circumstances.

45 The top edges of the bulkheads are preferably rounded over after the manner shown in the case of the gunwale plate 10 in Fig. 3.

11 is a step for the mast, riveted to the top of the buoyancy tank, and 12 are cleats 50 for foot rest bars.

The central buoyancy tank, being in the form of a deep continuous box girder with its sides well braced together, is very strong to resist bending stress, especially in the vertical direction, and as it is effectually secured all along to the boat, it adds very materially to the strength thereof.

I accordingly make use of this girder to sling the boat from the davits, the ordinary 60 slinging tackle being attached to the hooks 13 secured to the tank at its ends where it is further strengthened by the gussets 6 and the central bulkheads 9.

In the case of a steel boat the tank is, 65 as already stated, riveted thereto all along;

in the case of a wooden boat, it is securely bolted, strapped, cleated or otherwise fastened at frequent intervals to the frames of the boat so as to distribute the lifting stress throughout the structure. The additional 70 strength thus afforded, renders it safe to fully load the boat while still slung in the davits, which might be dangerous, and in some cases impracticable, in the case of a fully loaded boat of the ordinary kind slung 75 in the ordinary way.

The tank 5 might extend the whole length of the boat, or the spaces between the ends of the tank and the ends of the boat might be bulkheaded off and closed with a water-tight deck so as to form end buoyancy compartments, but for the reasons stated, I consider the construction as illustrated to be preferable, as it is safer and there is no difficulty in providing the required buoyancy 80 with the tank considerably shorter than the boat.

The tank 5 is not necessarily made integral with the boat as shown in the drawings; in the case of a wooden boat or where the 90 integral formation is otherwise unsuitable or undesirable, the tanks which are then self-contained may be secured in any convenient manner along the center line of the boat. 95

The buoyancy tanks and the bulkheads are shown as high as the thwarts will permit, as any greater height would cause some inconvenience, but they might obviously be carried higher if thought desirable. 100

The tanks are preferably galvanized all over, which not only protects them from corrosion, but improves their staunchness.

The invention is specially applicable to boats of the semi-collapsible type. Such 105 boats must of necessity be fitted with buoyancy tanks, and from their structure, their buoyancy tanks as usually arranged, are specially exposed to risk.

Boats constructed with buoyancy tanks 110 and bulkheads as described are not only materially strengthened by the girder-like formation of the tank, which is preferably incorporated with the boat, but the risk of foundering is materially reduced, as the tanks are not likely to be damaged by a collision or blow unless the boat as a whole is destroyed, and if any of the individual tanks should become damaged and flooded, the boat will not be so loaded as to affect its 115 stability.

Having now fully described my invention, I declare that what I claim, and desire to secure by Letters Patent is;—

1. In a ship's boat, in combination with a 125 central longitudinal buoyancy chamber, a series of bulkheads extending from the ends and sides of the chamber to the shell of the boat, substantially as described.

2. In a ship's boat, in combination with 130

a central longitudinal buoyancy chamber, a series of longitudinally yielding bulk-heads extending from the ends and sides of the chamber to the shell of the boat, substantially as described.

3. In a ship's boat, in combination, a water-tight buoyancy chamber of deep rectangular cross-section, extending longitudinally within the boat with its center line coincident with that of the boat, the sides of the chamber being flanged outwardly below
- 10

and riveted along the bottom of the boat so as to be incorporated with the structure thereof, and a pair of hooks, fixed one at each end of the said buoyancy chamber, for sling the boat, substantially as described.

In testimony whereof I affix my signature in presence of two witnesses.

ARTHUR ROBERT THOMAS WOODS.
